METHOD OF CLARIFYING SUGAR SOLUTION.

1,119,174.

Specification of Letters Patent.

Patented Dec. 1, 1914.

Application filed September 28, 1911. Serial No. 651,692.

To all whom it may concern:

Be it known that I, ERNST W. KOPKE, a citizen of the United States, and residing at Honolulu, Territory of Hawaii, have invented certain new and useful Improvements in Methods of Clarifying Sugar Solutions; and I do hereby declare the following to be a full, clear, and exact description of the invention, such as will enable others skilled in the art to which it appertains to make and use the same.

This invention contemplates a betterment in the art of disassociating and separating aggregate liquids and suspended solids of different densities by employing centrifugalization to better advantage.

The method described is peculiarly advantageous when applied to the epuration of the juices extracted from sugar cane during the manufacture of sugar, a field in which centrifugal separation has never been successfully accomplished. The invention does, nevertheless, constitute an improvement in the application of centrifugalization to the separation of liquids and suspended solids without regard to the branch of industry in connection with which it might be employed.

In the accompanying drawings, I have illustrated a centrifugal separator especially designed to carry into practice the method herein described and claimed.

In the drawing, Figure 1 is an elevation, partly in section; and Fig. 2 is a detailed section of a modified construction of the upper portion of the drum and casing.

The juices expressed from sugar cane contain many impurities which must be eliminated sooner or later during the process of obtaining the crystallized sugar, and owing to the intimate admixture of these impurities with the clear solution of crystallizable sugar and the slight differences existing between the specific gravities of the impurities and the clear juice, their economical separation by the centrifugal process has not been heretofore successfully accomplished. The practical methods resorted to for clarifying the juices have involved the use of settling tanks, sand filters, filter presses, and the like, which in every case have required the juices to remain under treatment for protracted periods, subjecting the sucrose to the danger of inversion,

and requiring the application of heat and reagents at times when impurities have been present, and the elimination of these impurities has been rendered more difficult thereby.

This invention contemplates a mode of centrifugally separating the clear juice from the solid impurities admixed therewith immediately upon the issuance of the juice from the expressing mill and at any time thereafter during the process of clarification when solid impurities are present, and this in a fraction of the time heretofore required, minimizing the danger of inversion, producing a more complete clarification of the juice, and effecting a considerable saving in time and labor. Furthermore, by this method, a greater percentage of the sugar content of the original juice may be economically recovered than has heretofore been deemed practicable.

The invention consists in the hereinafter particularly described method of subjecting the cane juice or other fluid substance to be clarified, to stratification and separation by centrifugalization, and this method involves a particular mode of introducing the juice into a rotating separator by first supplying it to an ante-chamber in the rotating centrifugal, and there gradually imparting to it the angular velocity of the separator before admitting it to the chamber in which it is to be stratified, in order that the disturbances incident to the acceleration of the juice to the angular velocity of the separator shall not occur in the stratifying chamber. The method also involves the manner in which the juice is caused to flow through the stratifying chamber in order that all stratification and interference of the substances of unlike density shall be avoided. Other important features consist in the manner in which the initial introduction of the juice is effected, the mode of recovering the clarified juice during the period of uninterrupted stratification and separation, and the manner in which the final body of juice is displaced and recovered prior to the discharge of the collected muds.

In order to show clearly the conditions to which the juice is subjected in the practice of this method by the use of the machines illustrated in the annexed drawing, it is deemed advisable to describe in detail the

structure of the machine, in connection with the description of the process which it is designed to carry out.

Referring to the drawing, rods *a* depend from a supporting head *A* which is designed to admit of a certain amount of oscillation as is usual in suspended centrifugal machines, and these rods *a* support a non-rotating casing *B*. The lower part of the casing *B* consists of a casting in the outer edge of which an annular gutter *C* is formed. Arms *D* project inwardly from the gutter *C* and support a ball step bearing *e* in which the lower end of a rotating shaft *E* is journaled. The upper end of the shaft *E* is journaled in a suitable bearing in the head *A*. A spider *F* has a long hub *f* which is rigidly secured to the shaft *E*, the arms of which spider carry a rotatable imperforate drum or annular chamber *G*. The drum *G* is cylindrical, its interior being smooth and unobstructed, and is provided with an in-turned flange *g* at its upper edge, while a peripheral annular ring *H* upon the spider *F* provides an inturned flange upon its lower edge. These inturned flanges *g* and *H* form the end walls of an annular stratifying chamber *I* which is adapted to contain a cylindrical body of liquid when the drum *G* is revolving. A flange *j*, substantially L-shaped in cross-section, is secured to the bottom of the drum *G* and forms an annular ante-chamber *J* opposite the outermost part of which a circular series of apertures *h* are provided in the bottom wall of the drum *G*, affording communication between the ante-chamber *J* and the stratifying chamber *I*. The supply pipe *k* supported on the casing *B* passes upwardly between the arms *D* and terminates in a flat nozzle *K* which lies with its mouth parallel with and at an acute angle to the normal liquid level (indicated by dotted line *a*) in ante-chamber *J* while the machine is in operation, and this nozzle *K* discharges in the direction of rotation of the machine, thus laying a flat ribbon of fluid upon the surface of the liquid in ante-chamber *J*. The juice flows with all its content of the heavier solid impurities from the ante-chamber *J* through the apertures *h* into the stratifying chamber *I*, as an inclination given the outer wall of the flange *j* deflects any mud which tends to collect thereon toward the apertures *h*. Reverting to the method of introducing the juice, attention is called to the fact that the thin ribbon of introduced liquid is laid upon the surface of the liquid already in ante-chamber *J* and does not immediately come into contact with any part of the rotating machine but, as it is moved outwardly by the succeeding layers of introduced juice, its angular velocity is gradually increased by friction with the preceding, faster-moving layer, until it comes op-

posite the apertures *h* when it will come in contact with the outer wall of the flange *j*, and will have attained the angular velocity substantially equal to that of the rotating separator. The liquid is then traveling at substantially the same speed as the apertures *h* and can flow through these apertures quietly into the stratifying chamber *I*; if the liquid has not quite attained the angular velocity of the drum, the walls of the apertures *h* will give it the necessary additional speed and it will enter the stratifying chamber *I* without causing any of the currents or disturbances which would be present if it were not already traveling at the same speed as the drum. However, the liquid entering the stratifying chamber *I* in a number of separate streams from the apertures *h* would cause striations in the body of the liquid within the chamber *I* which would be evidenced by channels appearing in the layer of mud which collects in the chamber *I* about the wall of the drum, and an uneven flow of the juice through the chamber *I* would result. To avoid this, I place a baffle ring *L* a short distance above the apertures *h* and cause the streams of liquid flowing into the chamber *I* through the apertures *h* to impinge against this ring and spread and flow outwardly over the outer edge of the ring *L*, where the several streams are caused to join and form a thin cylindrical sheet of liquid flowing upwardly through the stratifying chamber *I*. The baffle ring *L* extends with the liquid level and the countersunk bolts which support it are placed at points without the liquid in order that they may not cause any disturbance within the body of liquid.

The outer edge of the baffle ring *L* should be accurately concentric with the axis of rotation and should be so spaced from the wall of the drum that the rising cylindrical film of liquid enters the main body of the liquid in the stratifying chamber *I* and in passing therethrough undergoes a separation of its constituents of different densities, the heavier moving outwardly and the lighter inwardly, without interference.

At the upper edge of the rotating drum *G* the in-turned flange *g* is preferably provided with a channel *M* the lower wall *m* of which projects inwardly farther than the flange *g* and constitutes a dam for holding back any lighter impurities which might find their way into the stratifying chamber *I*. In the practice of clarifying sugar solutions, such lighter particles are few and they usually collect in small quantity upon the surface in ante-chamber *J* and are rarely driven deep enough to enter chamber *I* through apertures *h*. The outer wall of the channel *M* is provided with a circular series of apertures into which are slipped tubules *N*

through which the clarified juice rises into the channel M from that depth in the body of liquid in chamber I from which it is desired to be drawn, and these tubules used 5 of various lengths and quickly interengageable serve as convenient means for altering the depth from which the clarified juice is to be drawn. The channel M offers a convenient place from which the juice may be scooped in the well known manner if desired but usually it is allowed to overflow the edge of the flange g to be caught by the casing B and drained from the gutter C through outlet pipe O. The particular 10 construction of the upper edge of the rotating drum in Fig. 1, while convenient, is not essential to this process however, that shown in Fig. 2, wherein a dam P similar to ring L is used and the clarified liquid is allowed to overflow through apertures p in the flange g, serving quite as well. The discharge of the clarified juice at the upper 15 edge of the rotating drum must be so controlled however, that no disturbances are created within the stratifying chamber I.

A plow Q is mounted upon the lower end of a racked rod q which is mounted in a bracket R on the casing B and this plow Q is adapted to be moved downwardly into 20 and throughout the length of the drum G by the engagement of a pinion with the rack upon rod q, the pinion being actuated by a hand wheel r on the end of a lever S. The lever S is splined to the rod q and by its 25 annular movement the rod q may be turned to bring the plow into engagement with the inner surface of the drum G, in which position it operates to remove the layer of mud and may be moved throughout the 30 length of the drum by the hand wheel r.

In carrying this process into practice with the machine described, the machine is brought up to speed, which need not be so high as to be considered excessive for this 35 class of apparatus, a peripheral speed of 10,000 feet per minute having been found satisfactory in practice. Ordinarily the juice is then admitted through the nozzle K and in passing through the ante-chamber 40 attains the angular velocity of the machine. The juice gradually accumulates in the separating chamber until it reaches the normal liquid level indicated by dotted line x and the overflow of the clarified juice begins. 45 In certain exceptional cases it has been found that the first out-flow of juice from the machine is slightly turbid, and in that event it is well to interrupt the inflow through the nozzle K for a few minutes 50 and then re-establish it, when the turbidity will disappear and the separation may continue. The ribbon introduction and gradual acceleration of the juice in the ante-chamber J by avoiding any direct contact with parts 55 at speed is essential to avoid surcharging the

juice with air and creating disturbances that would follow to the stratifying chamber I. The period of continuous clarification and discharge of clarified juice obtains until a quantity of mud has collected in chamber I 70 which renders a discharge of the mud advisable. The supply of juice is then discontinued and a sufficient quantity of water is introduced to displace the balance of clarified juice which necessarily remains in chamber I. The machine is then slowed down, 75 which reduces the pressure upon the mud and allows it to expand much as a compressed sponge, and it absorbs the last introduced water and attains a consistency 80 which permits of its being plowed out with little or no difficulty at the reduced speed of the machine. The machine may now be speeded up and the operation repeated.

The machine illustrated embodies the subject matter of a separate application for United States Letters Patent, filed by me of even date herewith, and identified as Serial No. 651,692.

As hereinbefore pointed out but little floating scum and dross of the lighter impurities appear in the machine in connection with this process and this is the more remarkable in view of the fact that what does appear is but a small percentage of that 90 which collects from a similar quantity of juice when settling tanks are employed. The cause of the non-appearance of the lighter impurities is the conversion of the lighter fibrous matter into heavier impurities by the high pressure to which they are subjected while in suspension in the centrifugal because of the subsurface introduction of the juice into the separating chamber. This pressure ruptures the air cells within 95 their structure, releasing the air and destroying the buoyancy. They then become heavier than the solution in which they are suspended and collect with the muds, obviating the necessity of providing special 100 means for their removal.

Having thus described my invention what I claim is:

1. The method of separating liquids from substances suspended therein, by a process of centrifugal stratification, which consists in bringing the unstratified liquid containing the suspended substances, before its introduction into the stratifying chamber, up to the speed of the stratum into which it is to be introduced, introducing the liquid so accelerated into the stratifying chamber of the centrifugal beneath the surface of the liquid therein as an axially moving hollow cylinder and discharging by cylindrical overflow a chosen stratum of the separated liquid at the end of the stratifying chamber opposite to that at which the liquid was introduced; substantially as described. 115
2. The method of separating liquids from 120
3. The method of separating liquids from 125
4. The method of separating liquids from 130
5. The method of separating liquids from 135

1. Substances suspended therein, by a process of centrifugal stratification, which consists in bringing the unstratified liquid containing the suspended substances, before its introduction into the stratifying chamber, up to the speed of the stratum into which it is to be introduced, introducing the liquid so accelerated as an axially moving hollow cylinder beneath the surface of the liquid in the stratifying chamber of the centrifugal, wherein the movement of the particles in response to the centrifugal force is unobstructed, and discharging by cylindrical overflow a chosen stratum of the separated liquid at the end of the stratifying chamber opposite to that at which the liquid is introduced; substantially as described.
2. The method of separating liquid from substances suspended therein, by a process of centrifugal stratification, which consists in introducing the liquid containing the suspended substances at an acute angle upon a previously introduced body of liquid contained in a smooth unobstructed annular ante-chamber of a centrifugal, so causing each stratum of the introduced liquid to be accelerated by the preceding stratum as it moves outwardly in said ante-chamber until it acquires substantially the angular velocity of the stratum into which it is to be introduced, and discharging by cylindrical overflow a chosen stratum of the separated liquid at the end of the stratifying chamber opposite to that at which the liquid was introduced; substantially as described.
3. The method of separating liquid from substances suspended therein, by a process of centrifugal stratification, which consists in introducing the liquid containing the suspended substances at an acute angle upon a previously introduced body of liquid contained in a smooth unobstructed annular ante-chamber of a centrifugal so causing each stratum of the introduced liquid to be accelerated by the preceding stratum as it moves outwardly in said ante-chamber until it acquires substantially the angular velocity of the stratum into which it is to be introduced and causing the outer accelerated stratum of introduced liquid in said ante-chamber to flow axially as a hollow cylinder into a stratifying chamber within the rotating centrifugal.
4. The method of supplying fluid substances to a rotating centrifugal separator that they may enter the stratifying compartment of the separator with the proper angular velocity and without causing disturbances of the liquid undergoing stratification, which consists in introducing the fluid at an acute angle upon a previously introduced body of liquid contained in a smooth unobstructed annular ante-chamber of a centrifugal so causing each stratum of the introduced liquid to be accelerated by the preceding stratum as it moves outwardly in said ante-chamber until it acquires substantially the angular velocity of the stratum into which it is to be introduced and causing the outer accelerated stratum of introduced liquid in said ante-chamber to flow axially as a hollow cylinder into a stratifying chamber within the rotating centrifugal.
5. In a method of clarifying sugar and similar solutions, the introduction axially into a previously introduced body of fluid in the stratifying chamber of a rotating centrifugal separator, of a thin, substantially tubular film of fluid which has previously been brought to substantially the angular velocity of the separator; substantially as described.
6. In a method of clarifying sugar and similar solutions which consists in axially introducing into a previously introduced body of fluid contained in the stratifying chamber of a centrifugal separator, a thin, substantially tubular film of fluid which has previously been brought to substantially the angular velocity of the separator, passing the fluid so introduced through the stratifying chamber and subjecting it during its passage to centrifugal stratification and removing the clarified solution, the fluid so introduced through the stratifying chamber substantially as described.
7. A method of clarifying sugar and similar solutions which consists in introducing the fluid at an acute angle upon a previously introduced body of liquid contained in the stratifying chamber of a centrifugal separator, a thin, substantially tubular film of fluid which has previously been brought to substantially the angular velocity of the separator, passing the fluid so introduced through the stratifying chamber and subjecting it during its passage to centrifugal stratification and removing the clarified solution, the fluid so introduced through the stratifying chamber substantially as described.
